UNITED STATES PATENT OFFICE.

JAMES J. TURNER, OF RICHMOND, INDIANA, ASSIGNOR TO HIMSELF AND
JOHN F. MILLER, OF SAME PLACE.

DEVICE FOR ACTUATING SIGNALS, SWITCHES, &c.

SPECIFICATION forming part of Letters Patent No. 374,914, dated December 13, 1887.

Application filed March 3, 1887. Serial No. 229,489. (No model.)

To all whom it may concern:

Be it known that I, JAMES J. TURNER, of Richmond, county of Wayne, State of Indiana, have invented a new and useful Improvement 5 in Devices for Actuating Signals, Switches, and Switch-Locks, of which the following is a true and exact description, due reference being had to the accompanying drawings, which form a part of this specification.

10 The object of my invention is to provide a simple and efficient device whereby a single operating-lever may be made to actuate two or more independent signals, switches, or switch-locks; and it consists of a link arrangement 15 having a movable fulcrum actuated by one of the operating-levers, said link having an oscillating motion given to it by means of another operating-lever, and in turn actuating a switch-signal or switch-lock in one direction 20 or another, according to the position of its fulcrum, or operating one of two attached switches, signals, or switch-locks connected to the link at different points; also, in a special arrangement of my improved links, whereby 25 the position of a switch is made to regulate and govern which of two signals or signals and switch-locks connected with an operating-lever shall be actuated, and in the special devices hereinafter described, and which I have 30 found to be efficient in adapting my invention to use.

Reference being had to the accompanying drawings, which illustrate my invention in two modes of application, Figure 1 illustrates my 35 improved link arrangement as adapted to actuate either of two switches, &c., according to the position of the lever which regulates the position of the fulcrum-point. Fig. 2 shows the device of Fig. 1 in perspective, showing 40 also an adaptation of my link arrangement by which the change of the fulcrum position results in changing the direction of motion given to a switch or switch-lock. Fig. 3 is a front view of the combined link arrangement shown 45 in Fig. 2. Fig. 4 is a view of the link device for changing the direction of movement of its connected element, showing in dotted lines the different motions given to the link by the same impulse; and Fig. 5 is a perspective view of 50 the devices shown in Figs. 2 and 3, showing also their operating-levers and connections

therewith, the whole being organized to carry out a particular design, as hereinafter described.

A, A', and A² are operating-levers, such as 55 are ordinarily contained in the lever-frame of an ordinary railway signal-tower.

B B', &c., are T-heads at the ends of levers A A', &c.

C is a connecting-rod pivoted to lever A' at 60 B² and to a bell-crank, F, at c; G, a connecting-rod leading to a switch and actuated by the other end of bell-crank F.

E is a connecting-rod pivoted to lever A' at B³, and at its other end to a lever-arm, M, which 65 is secured to and actuates a rotating shaft, m.

L and L' are also lever-arms secured to shaft m and having forked lifting-arms K K', pivoted to their outer extremities at l and l'.

k k' are pivots secured in the ends of the 70 forked levers K K' and in guides forming part of the stationary frame-work and running substantially parallel with the slot in links J J' when in their medial position, so that the pivots k k' may be moved from top to bottom of 75 said slots, but are held securely against lateral movement. These pivots serve as fulcrum-points for the slotted links J J'. These links are at their lower ends provided with pins n n', which are secured in slotted guides N N'. 80

I and I' are respectively the rods by which the links J and J' are actuated, and these rods are in turn operated through bell-crank H and H' and rods D and D' by means of levers A and A².

O and O' are operating-connections secured 85 to the link J, and by means of which two signals or other devices are respectively operated. The rod I is secured to the link J in the middle of the slot, and the lines O and O' 90 are fastened at points in line with the two extremities of the slot, so that that line which is at the point of the slot where the fulcrum-pin k rests is not moved when the link is moved, while the other line fastened at the free end of 95 the slot is moved.

In Fig. 1, the fulcrum k being at the bottom of the slot, the dotted lines J² represent the movement of the link, O² its effect on the line O, and the fulcrum being at the top at k² the dotted lines J³ represent the movement of link J, and O³ its effect on line O'.

In the case of link J' , which has but one operating-connection, R , the actuating-shaft I' is secured in such position with relation to the slot that the travel of the point below the slot 5 to which rod R is connected will be the same in either direction, according as the fulcrum k' is at the top or bottom of the slot.

In Fig. 4 are illustrated the different motions given to the link J' , according to the position of the fulcrum, and it will be noticed that this arrangement of the link is well adapted to operate a three-throw switch, and it is also suitable for operating a new double switch-lock, which I have invented and for 15 which I am about to file an application for a patent, as well as to many other uses.

It is only necessary to call attention to the fact that the positions of the fulcrums K K' are governed by the lever A through the shaft m 20 and the devices already described.

Referring now to the special combination of links and actuating devices shown most clearly in Fig. 5, and which is designed for a special use—to wit, making the same signal-lever operate either one of the two signals on different lines, according as the switch is set for one or the other, and operating either one of two switch-locks to lock the switch in either 25 position— G is the switch-connection actuated in the usual way by lever A' . By means of a rod, E , also actuated by lever A' , as shown, the fulcrum-points k k' of the two oscillating links J J' are moved up and down, according to the position of the switch-lever and switch.

35 To link J , having its actuating-rod I attached at the middle of its slot, are connected the signal-lines O O' , one of which is thrown out of operative position and the other into operative position by each movement of the 40 fulcrum k in the slot, as is evident. The signal to be operated is thus governed by the position of the switch, the signal on the disconnected line being left in the "danger position."

To link J' , having the two extremes of its 45 slot arranged with respect to the point of connection i' of rod I' , so that the movement of the point where rod R is attached shall be substantially the same in extent in either direction, is attached the rod R , which may be 50 connected with a double bell-crank lever having switch-locks attached at each extremity—such as described in another application which I am about to file—so that either one of the said connected locks will be operated according to the position of the fulcrum; or any 55 other desired connection with other switches, locks, or signals may be made through said rod R .

While I prefer to use slots, as shown in my 60 links and guides, it is of course evident that sleeves or any other well-known device for making a movable pivoted connection between two pieces of mechanism may be substituted for such slots, and I do not wish to be understood as limiting my claims to the particular 65 kinds of connections and points shown in the drawings.

Having now described my invention, what I claim as new, and desire to secure by Letters Patent, is—

70 1. In a device for actuating two or more switches, switch-locks, or signals by a single lever, the combination of the stationary guide N , the link J , pivoted to said guide at one end and having a movable fulcrum, a device for regulating the position of the movable fulcrum, a device for operating link J , attached to it between the extreme positions of the movable fulcrum, and one or more connections to the device or devices to be actuated, all substantially as and for the purpose specified.

75 2. In a device for actuating two or more switches, switch-locks, or signals by a single lever, the combination of the stationary guide N , the link J , pivoted to said guide at one end and having a movable fulcrum secured to a forked connecting-rod extending over the said link, a device for regulating the position of the movable fulcrum through the forked connecting-rod, a device for operating link J , 80 attached to it between the extreme positions of the movable fulcrum, and one or more connections to the device or devices to be actuated, all substantially as and for the purpose specified.

90 3. In a device for operating two or more signals, switches, or switch-locks by a single lever, the combination of the stationary guide N , a link pivoted at one end in said guide, a movable fulcrum sliding along said link, one 95 or more operating-connections attached to said link, a fulcrum-holding device connected with and moved by one of the levers in the signal-house, substantially as described, a device for moving the link, and through it the operating connection or connections secured between the extreme positions of the movable fulcrum, and a lever in the signal-house connected with said link-moving device and actuating it, substantially as described.

100 4. In a device for actuating either of two lines of connection with switches, switch-locks, or signals, the combination of the stationary guide N , the link J , pivoted at one end to said guide and having a fulcrum-pivot movable 105 along its length, a device for moving said fulcrum-pivot, connecting-lines O O' , secured to the link at the two extreme points between which the fulcrum-pivot moves, and a device for moving the link on its pivot, connected 110 with the link at a point midway between the extreme points of the fulcrum-pivot's movement, all substantially as described, so that one connecting-line remains stationary while the other is operated.

115 5. In a switch and signal actuating device, the lever A' , connecting with the switch-actuating connection G and with a fulcrum holding and actuating device, K , substantially as shown and described, in combination with a 120 fixed guide, a link, J , secured at one end in said guide and pivoted on the movable fulcrum, the lever A , connected with and actuating the link, substantially as specified, and

one or more connecting-lines attached to the link, as and for the purpose shown and described.

6. In a switch and signal actuating device, 5 the lever A', connecting with the switch-actuating connection G and with two fulcrum holding and moving devices, K K', substantially as shown and described, in combination with fixed guides, links J J', pivoted at one end in 10 said guides and having slots for the movable fulcrums arranged with respect to their points of attachment to their actuating rods, sub-

stantially as shown and described, connections O O', attached to link J at the extreme points of the fulcrum-slot, a connection, R, attached 15 to link J' at a point where the movement about each end of the fulcrum-slot is substantially the same, and connections with the operating-levers to said links, all substantially as and for the purpose shown and described.

JAMES J. TURNER.
